(57) **CLAIM**

The invention claimed is the ornamental design for a chair, as shown and described.

DESCRIPTION

FIG. 1 is a front elevational view of a chair showing a first embodiment of my new design;

FIG. 2 is a rear elevational view thereof;

FIG. 3 is a top plan view thereof;

FIG. 4 is a bottom plan view thereof;

FIG. 5 is a right side elevational view thereof (the left side being a mirror image thereof);

FIG. 6 is a perspective view thereof.

FIG. 7 is a front elevational view of a chair showing a second embodiment of my new design;

FIG. 8 is a rear elevational view thereof;

FIG. 9 is a top plan view thereof;

FIG. 10 is a bottom plan view thereof;

FIG. 11 is a right side elevational view thereof (the left side being a mirror image thereof); and,

FIG. 12 is a perspective view thereof.
